UNITED STATES PATENT OFFICE

WOLDEMAR GEORGE NOLCKEN, OF LONDON, ENGLAND

METHOD OF AND MEANS FOR REFRIGERATION

Application filed July 13, 1931, Serial No. 550,388, and in Great Britain July 23, 1930.

This invention relates to refrigerating apparatus of the ice box type.

In refrigerators of this type a source of extreme cold, such as solid CO_2 , commonly known as "dry ice", has been used and in order to prevent the too rapid dissipation of the refrigerant various means have been provided to control the evaporation. All such means function as insulators of low heat conductivity and they have been introduced between the refrigerant and the refrigerated commodity, as for example the ice blanket which surrounds and protects the subliming hydrated carbon dioxide ice in the product known under the trade mark "Hydriice".

In all known arrangements of this kind, however, a certain amount of energy obtained from the solid refrigerant has been dissipated without any useful advantage being obtained therefrom since the heat flow takes place through a large temperature range without doing any work.

The object of the present invention is to provide an improved refrigerating apparatus of the ice box type in which this loss of energy is utilized so that more economic refrigeration is produced.

According to the present invention refrigerating apparatus of the absorption type is operatively disposed between the solid refrigerant and the refrigerating chamber, the energy necessary for driving the apparatus being that hitherto wasted in the manner described.

In carrying out the invention I may use the known refrigerating apparatus comprising a generator, condenser, absorber and evaporator. For the purpose of the present specification and claims the generator will be referred to as an evaporator since, as will be evident hereafter, the generator employed has the function solely of an evaporator.

In carrying out the invention the apparatus is rearranged in such a way that the two evaporating chambers are placed in the refrigerating chamber and the dry ice may be associated with the condenser in the same refrigerating chamber; or alternatively it may be disposed in a separate refrigerating chamber. The latter course may be adopted

where it is desired to refrigerate to an extremely low temperature.

In carrying out the invention the heat flow in the apparatus is arranged in such a way that the absorber has the highest temperature, the condenser the lowest temperature, and the two evaporators have an intermediate temperature. This will be more fully explained hereafter.

It is customary to distinguish between absorption and adsorption, the former being essentially a process of dissolution, as for example ammonia in water, whilst the latter is a process of surface adsorption, as for example with silica gel or charcoal in contact with vapours. In order to avoid confusion, both these processes will be referred to as "absorption", it being understood that the general thermodynamic principles involved are alike in both cases.

Whereas in absorption machinery of the known type, the energy for producing refrigeration is derived from a source of heat, such as steam, electricity, gas or the like, in the apparatus according to the invention the energy for producing refrigeration is, as above set forth, derived from a source of intense cold, such as solid carbon dioxide for example.

Various ways of carrying out the present invention are illustrated by way of example in the accompanying drawings, wherein:—

Fig. 1 is a diagrammatic representation of the heat flow in known refrigerating apparatus of the absorption type,

Fig. 2 is a diagram of the heat flow in apparatus according to the present invention,

Fig. 3 shows diagrammatically the application of the invention to an ammonia-water absorption plant of the open-cycle type,

Fig. 4 illustrates in diagrammatic form an intermittent ammonia-water machine.

Fig. 5 is a diagrammatic view of a modified form of apparatus using a solid absorbent.

Referring first to Figs. 1 and 2, Fig. 1 is a diagrammatic representation of a closed circuit absorption machine of a well known type, and Fig. 2 represents the same machine rearranged according to the invention. Alike

reference letters in Figs. 1 and 2 denote alike parts.

The shaded portion LMNO represents a section through the heat insulating wall of a cold room or ice box. Parts of Figs. 1 and 2 which are inside the cold room are shown below the band LMNO and parts shown above the band are outside the cold room.

The working temperatures of the various parts of the two machines illustrated in Figs. 1 and 2 respectively, correspond to their respective levels in the diagram, warmer parts being shown above the colder ones, and with reference to the common temperature scale 15 on the left side of the drawings.

It will be understood that the range of possible working temperatures of the two machines is not limited to this scale.

Referring first to Fig. 1, G is the generator, 20 A the condenser, C is the evaporator and E the absorber. The refrigerant passes through the circuit in the order, generator to condenser, condenser to evaporator, evaporator to absorber, and absorber to generator, as 25 shown by the plain lines and arrows. The generator is heated by steam, electricity, gas burner or the like, and the absorber and condenser are cooled by water or air.

In every absorption machine there are 30 necessarily three working temperatures, T, T1 and T2, to be considered, and two working pressures. In Fig. 1 the generator G is at the high temperature T of the source of heat and the working medium within it is at the high 35 working pressure. The condenser A is at the intermediate temperature T1 of the cooling water or air, and at high pressure. From the condenser A the high pressure refrigerant flows into the evaporator C through the 40 expansion valve V, which lowers its pressure. The evaporator C contains low pressure refrigerant at the low temperature T2 of the cold room. In the absorber E, the refrigerant vapour from the evaporator C is absorbed at 45 the low working pressure and intermediate temperature T1. The pump P compresses to the high working pressure, and conveys to the generator G the absorption solution from E, saturated with refrigerant. The return flow 50 of the dilute solution from the generator to the absorber is omitted in the diagram. The high pressure side of the system is shown in double lines and the low pressure side in plain lines.

55 The direction of the heat flow through the machine is shown by the dotted lines and arrows.

From the source of heat a quantity Q of heat at the high temperature T flows into the 60 generator G and is rejected to cooling water or air by the condenser A at the intermediate temperature T1. This causes a further quantity Q2 of heat to be absorbed by the evaporator C at the low temperature T2 of the cold room, and to be rejected to cooling water or

air by the absorber E at the intermediate temperature T1.

The ratio of heats for the ideal reversible process is expressed by the known equation:—

$$\frac{Q2}{Q} = \frac{T2 (T - T1)}{T (T1 - T2)}$$

Fig. 2 represents the absorption machine rearranged according to the invention. The absorber E is cooled by water or air and the 75 condenser A by dry ice. The generator G and evaporator C absorb heat from the cold room. The refrigerant circulates in the same direction as in Fig. 1 and is indicated by the plain lines and arrows, but the high and low pressure sides are reversed. The evaporator C and absorber E contain the high pressure refrigerant, and the generator G and condenser A are at low working pressure. The pressure pump P forces the liquid low pressure refrigerant from the condenser A into the evaporator C and the concentrated absorption solution from the absorber E passes into the low pressure side of the system through the expansion valve V. The return flow of the 90 weak absorbent solution from the generator G to the absorber E through a pressure pump is omitted in the diagram Fig. 2.

The four organs of the machine are displaced with reference to the three working 95 temperatures T, T1 and T2, and all temperatures are much lower than in Fig. 1. Accordingly the two working pressures are also lower.

Heat flows through the machine in the same 100 direction as in Fig. 1 with reference to the organs of the plant, namely from the generator G to the condenser A and from the evaporator C to the absorber E as indicated by the dotted lines and arrows. With reference to the working temperatures, however, the direction of the heat-flow is reversed. Thus heat is taken in at the intermediate temperature T1 and rejected at the high and low temperatures T and T2 respectively. 110

A quantity Q2 of heat is rejected by the condenser A to the dry ice at the temperature T2 and a quantity Q of heat is rejected by the absorber E to cooling water or air at the temperature T. Both heats Q and Q2 are absorbed in the cold room at the temperature T1 by the generator G and the evaporator C. 115

The heat equation for the ideal reversible absorption process may be transposed thus:— 120

$$\frac{Q2 + Q}{Q2} = \frac{T (T1 - T2)}{T2 (T - T1)} + 1$$

when it expresses the ratio of heats removed 125 from the cold room to the heat rejected to the dry ice for any given range of working temperatures. As can be seen this ratio is at all times greater than unity, that is to say, the quantity of heat withdrawn from the cold room is at all times greater than the quantity 130

of heat absorbed by the evaporating dry ice, the balance being rejected to the cooling water or air by the generator.

Stated briefly—in absorption machines, such as shown for example in Fig. 1, a quantity Q_2 of low temperature heat is absorbed in the cold room, pumped up to a higher temperature level of cooling water or air to which it is rejected. The energy for the pumping of heat is supplied by the fall of the high temperature heat Q from the generator to the low temperature level of the condenser.

In the rearranged absorption machine (Fig. 2) this energy is supplied by the fall of low temperature heat from the generator to a still lower temperature level of the condenser.

In both machines, the part of the system comprising the generator and condenser acts in the manner of a heat engine, and the part comprising the evaporator and absorber in the way of a heat pump, the latter being driven by the former. Whereas in the arrangement shown in Fig. 1 the heat engine works at a higher temperature level than the heat pump, in Fig. 2 the heat pump is at a higher temperature level than the heat engine. Accordingly, the working pressures within the two systems are also reversed. In Fig. 1 the heat engine works at high pressure and in Fig. 2 the pump. Such reversal of the working pressures is provided by interchanging the pump P and the valve V as in Figs. 1 and 2.

In order to drive an absorption machine by cold instead of by heat, means must be provided for the reversal of the working temperatures and pressures, that is to say the portion of the machine which acts as heat engine must work at lower temperatures and pressures than the portion which acts as heat pump.

In absorption machinery of the closed cycle type, wherein a pressure equalizing inert gas is used, this gas is in the circuit between the evaporator and absorber, that is to say the part which functions as heat pump, is at a lower partial refrigerant vapour pressure than the part which works as heat engine, the total pressure throughout the system being the same.

The machine may be rearranged according to the invention by placing the pressure equalizing gas in circuit between the generator and condenser, that is in the region which acts as heat engine, and which must be at a lower partial pressure and temperature than the heat pump. A machine rearranged in this manner is illustrated in Fig. 3.

In absorption machinery of the open cycle or reversible type, the whole machine operates alternately as heat engine and as heat pump, both operations being carried out intermittently one after the other. During the

generating period, when the machine acts as heat engine, the pressures and temperatures throughout the system are high and during the absorption period when heat is pumped from the evaporator to the generator-absorber, the working pressures and temperatures are low.

In accordance with the invention a reversible absorption machine may be arranged in such a way that the generating period takes place at a lower temperature and pressure than the absorption period. A machine rearranged in this manner is illustrated in Fig. 4. Fig. 5 illustrates a similar arrangement using a solid absorbent.

Referring to Fig. 3 of the drawings, A is the ammonia condenser, which is kept at -109 degrees; with CO_2 ice. The liquid ammonia flows by gravity through the outlet pipe B into the evaporator or boiler C, which refrigerates the insulated cold chamber LMNO (dotted line). The dry ammonia vapour formed in the boiler flows through the pipe D into the absorber E, where it is absorbed by water, kept at a constant temperature by cooling water or air. The warm strong liquor ammonia from the absorber flows through the pipe F into the generator G, and the cold weak liquor from the generator returns to the absorber through the pipe H. The generator G is connected to the condenser A by two pipes J and K wherein an inert gas circulates between the condenser and the generator. The gas space in the generator G, the two pipes J and K and the gas space in the condenser A all contain the inert gas, which is prevented from escaping into the evaporating side of the system by the liquid seal in the pipe B. The ammonia is evaporated from the liquor in the generator at cold room temperature and low partial pressure into the inert gas. The gas saturated with ammonia rises in pipe J and the dry gas falls in pipe K. In the condenser A the ammonia gas mixture is cooled below the dew-point and the ammonia condensed. The pipes J and K are disposed as counterflow heat interchangers.

It will be observed that in general for every lb. of ammonia condensed in contact with the CO_2 ice, another lb. is absorbed in the absorber and the heat of absorption rejected to the cooling water or air; whereas two lbs. are being evaporated inside the cold room, one in the generator G and the other in the evaporator C. It will also be observed that the chemical heat of combination of ammonia and water, which is exothermic, assists the process of refrigeration, whereas in the absorption plant proper it counteracts it.

Within the condenser A, the receptacle R, is disposed in a manner used for the construction of vacuum flasks. The container R may be charged with dry ice from without the cold chamber, and is protected by an extra heavily insulated lid. The condenser A is

- also heat insulated, on the outside, i. e. against the air in the cold room, internal baffles are suitably disposed within the clearance space formed by the container R and the condenser A, with a view to increasing the total internal surface of condensation, as well as to circulate the mixture of gases and vapours through long and tortuous channels. Sufficient clearance is provided for the formation of a coat of solid NH₃ on the outer surface of the container R. The lower portion of the condenser A forms a sump, wherein the liquid NH₃ collects.
- From the bottom of the condenser A, the liquid NH₃ flows into the evaporator C, through the U-shaped pipe B. The difference in the hydrostatic level of the liquid NH₃ in the two limbs of the U-shaped pipe B, provides the pressure head for the pumping of the liquor in the pipe H. Preferably the U-pipe B is heat-insulated against the cold room, in order to avoid or reduce to a minimum any possible heating of the highly subcooled NH₃ up to boiling point, and the resulting formation of gas bubbles in the U-pipe B.
- From the evaporator C, the liquid NH₃ may be made to circulate in the known manner through the evaporator coil C₁. In order to provide a separate temperature control, a magnetically operated stop valve W may be fitted, the said valve being connected to, and operated by, a thermostat located in the cold chamber. Alternatively, several temperatures may be provided in several cold chambers by connecting the container C to a plurality of evaporator coils. Each coil may be operated by a thermostatically controlled stop valve.
- The dry and saturated NH₃ vapour, resulting from the evaporation of the liquid in the evaporator C collects in the top part of the container C, and flows through the S-shaped pipe D into the weak liquor pipe H. The pipe D is in heat inter-change with the pipe F. The superheated ammonia vapour is discharged into the rising limb of the U-pipe H, when it produces the pumping of the weak liquor from the generator to the higher level of the absorber E, in the known manner of gas lifts. In the absorber the solution is made to flow over pipes and baffles, wherein the cooling water is circulated. From the bottom of the absorber E, the warm rich solution flows by gravity through the U-pipe F into the generator G. The pipes F and H are disposed in counterflow heat inter-change.
- The de-aeration device S is of the known type and is fitted between the absorber E and the generator G, for the purpose of returning to the generator any non-absorbable gases which have escaped into the evaporator side of the system. Such escape of inert gases

from the condenser side of the system could for example take place when the plant is out of action for some time.

The generator G is provided on the outside with fins and ribs or other suitable devices, for the purpose of increasing its heat conducting surface. Inside it the solution delivered by the pipe F, flows over a plurality of internal baffles, which spread the solution out into thin sheets, exposing a maximum of liquid surface to the inert gas, which enters by the pipe K and rises to the top of the generator. In contact with the strong liquor the inert gas becomes saturated with NH₃ vapour and rises to the top of the generator G. The weakened solution collects at the bottom of the generator G and is returned to the absorber E through the pipe H.

The inert gas, saturated with ammonia, rises in the pipe J in consequence of its reduced specific weight and higher temperature. (Hydrogen, which is usual in absorption plants, is therefore not suitable as an inert medium. Nitrogen may be employed, or any of the heavier inert gases). In the condenser A the ammonia content of the gas in the pipe J is condensed and precipitated to the bottom of the vessel A, whence it flows into the pipe B. The cold inert gas from the condenser, having deposited its ammonia content, descends through the pipe K in consequence of its increased density and lower temperature, and is returned to the generator G.

The pipes J and K are disposed in heat inter-change. This heat inter-change is not complete, and the resulting thermosyphonic circulation assists and accelerates the natural gravity circulation of the mixture of gases and vapours.

As may be seen from Fig. 3 the pressure of the pure refrigerant vapour in the evaporator C and the pipe D is slightly higher than the pressure in the inert gas cycle. The balance is taken up by the column of liquid ammonia in pipe B, which provides the necessary pressure for pumping the absorption solution in the gas lift in pipe H. An increase in pressure in C tends to accelerate the action of the gas lift and with it to speed up the circulation throughout the system. A fall in pressure in C tends to slow down the circulation. When the pressure in C is equal to or less than the pressure in the inert gas circuit, the gas lift stops and all circulation in the system ceases.

The pressure in C is the saturated vapour pressure of the boiling liquid refrigerant and is determined by the temperature of the boiling liquid. The pressure in the inert gas cycle is the combined partial pressures of the inert gas and the refrigerant vapour given off in the generator E. Whereas the vapour pressure of the refrigerant varies within wide limits with the temperature the inert gas

pressure varies but little. A rise in cold room temperature therefore tends to produce an excess pressure in C, causing the circulation to be accelerated and a fall in the cold room temperature produces an excess pressure in the inert gas cycle, causing the circulation to slow down or stop altogether.

The temperature at which the two pressures are equal is the lowest temperature which can be reached in the cold room. The amount of inert gas initially charged into the machine determines this temperature, large quantities of gas producing high pressures and temperatures, and small quantities low pressures and temperatures.

In this way an automatic temperature control is provided by the inert gas, which may be charged into the machine up to a predetermined pressure corresponding to the lowest temperature limit in the cold room.

In Fig. 3, the condenser A, evaporator C and absorber E are all three in the same cold room. It will be understood that two cold rooms could be provided and kept at widely different temperatures, by placing the condenser A in the coldest room and C and E into the warmer one. The coldest room would be cooled by the direct action of the intensely cold dry ice contained in the receptacle R.

The absorber has been described as of the water-cooled type, but it will be understood that an air-cooled absorber may equally well be used, provision being made for suitable baffles, fins or ribs on the outer surface of the absorber, to ensure efficient heat transmission to the surrounding atmosphere. Adequate air circulation over the heat transmitting surfaces should also be provided.

Refrigerating apparatus as described consists of a series of steel pipes and containers suitably disposed and all welded together to form an hermetically closed system, provided where necessary with baffles, fins and webs to produce surface effects where required and the necessary heat interchanges as will be readily understood.

Referring now to Fig. 4, A is a condenser evaporator, which is provided with a compartment S, in which carbon dioxide ice may be placed. G is the generator and E the absorber which may be air or water cooled. The dotted line LMNO represents a section through the cold-room or refrigerator.

At the beginning of the generating period, almost all the ammonia is dissolved in the strong warm aqua contained in the absorber. The remainder of the system contains superheated dry ammonia vapour which is in pressure-temperature-concentration equilibrium with the liquor in the absorber.

When the solid carbon dioxide is placed into the container S, the temperature in the condenser is lowered and condensation of the ammonia vapour takes place on the outer

walls of the container S. The liquid condensate falls to the bottom of the vessel A, where it accumulates. The rapid fall of pressure throughout the system causes the strong liquor in the absorber E to be syphoned over into the generator G through the pipe H.

Evaporation of the ammonia from the liquor in the generator and condensation in the condenser proceeds until the concentration - pressure - temperature equilibrium corresponding to the low condenser temperature is reached. When all the carbon dioxide has evaporated, the process automatically reverses. The pressure throughout the system rises, the weak liquor is syphoned back into the absorber and absorption of the ammonia vapour evolved in the condenser-evaporator A by the liquor continues until the original pressure-temperature-concentration equilibrium is reached again, and the plant is ready for re-icing. The water vapour, which is entrained from the generator and condenses and gradually accumulates in the condenser-evaporator, may be periodically returned to the generator through a bypass pipe.

During the generating period, the machine works at a lower temperature than during the adsorption period. This feature is useful in railway and motor van refrigeration, where intense initial refrigeration is required, in order to precool quickly a warm vehicle after it has been iced up and before it starts on its journey.

The respective dimensions of the container S and the two communicating vessels G and E are such that the combined total weight of ammonia and water in the system is equal to the weight of the dry ice in S, when completely filled. The pressures within the system are those of the saturated ammonia solution and depend on the temperature of the solution. As there is no source of heat the pressures are low and the machine may be made of comparatively light material.

Instead of a water-ammonia system a solid adsorbent such as silica gel may be used with sulphur dioxide or any other suitable refrigerant.

The solid cannot conveniently be transferred into and out of the refrigerator as can the liquor; hence other methods must be used for the purpose of conveying heat from the refrigerator to the cold adsorbent during the icing period and for rejecting heat from the hot adsorbent to the cooling water or air during the adsorption period.

Reference is now had to Fig. 5. A is the condenser and S the dry ice receptacle. The evaporator coil C is connected to the condenser as shown, and may be of any suitable shape or size. The solid adsorbent is in the heat insulated container E, which communicates with the condenser A through the pipe

D. LMNO is a section through the roof of the cold room.

The two pipes J and K each contain a volatile liquid and are hermetically sealed off, each forming a separate condenser-evaporator circuit. The evaporator coil of the pipe J and the condenser coil of the pipe K are both inside the container E and are shown alongside each other in Fig. 5 in order to avoid ob-
10 security. The two coils may be threaded into each other to form a cylindrical container for the adsorbent, provision being made for good internal thermal contact as will be under-
stood.

15 In the well known manner of condenser-evaporator circuits the pipe K conducts heat from the cold room into the container E and the pipe J from the container E into the outer atmosphere.

20 The adsorption system works in the same way as the intermittent ammonia water absorption machine shown in Fig. 4. During the generating period, the refrigerant condenses in contact with the dry ice, and the
25 adsorbent gives off refrigerant and is thereby cooled. Heat flows through the pipe K from the cold room into the adsorber E. During the adsorption period the process is reversed. The refrigerant evaporates in C and the vapour is adsorbed in E. The heat of adsorption is rejected to the atmosphere through the pipe J.

25 W is a stop valve in the vapour return line of the evaporator C; the valve W is operated by a thermostat located in the cold room, for the purpose of providing a temperature control.

30 At the predetermined low cold room temperature at which the thermostat is set to operate, the valve W closes the return pipe of the evaporator C. Vapour builds up in the evaporator coil and the liquid refrigerant is driven back into the sump of the heat insulated condenser A. No more heat is with-
35 drawn from the cold room by the evaporator C until the temperature rises again and the thermostat opens the valve W. When W is shut the temperature and pressure in A falls rapidly and the evolution of vapour from the adsorbent increases. The pipe K contains a
40 small quantity of an inert gas, together with the volatile liquid, which prevents the evaporator coil of K from falling below a predetermined temperature, corresponding to the pressure of the inert gas, as is well known. The valve W opens whenever the temperature rises. Such rise may be caused by exhaustion
45 of the adsorbent or of the dry ice supply. In both cases refrigeration is taken over automatically by the evaporator C.

50 The application of the invention is not limited to solid carbon dioxide only, but may be applied in every instance, where the differ-
55 ence in temperature between the refrigerant

and refrigerator is of sufficient magnitude to warrant the interposition of a reversed absorption or adsorption plant, for the purpose of increasing the quantity factor of the heat removed from the refrigerator by reducing
60 the intensity factor of the heat drop. For example, liquid air and other cold liquefied gases would serve the same purpose as the CO₂, but in practice the latter should be used on account of its relative cheapness.

75 What I claim and desire to secure by Letters Patent is:—

1. In refrigerating apparatus of the ice-
80 box type, the method of producing an additional refrigerating effect by interposing be-
tween the refrigerant and the refrigerating chamber, a refrigerating apparatus working on the well known absorption principle, op-
erated by the existing flow of heat from the refrigerating chamber to the refrigerant—
85 said method consisting in condensing a va-
pour in heat exchange with the refrigerant, evaporating the condensate at a higher pres-
90 sure and temperature in heat exchange with the refrigerating chamber, absorbing the va-
pour in an absorption medium at a still higher temperature in heat exchange with a cooling medium, and expelling the vapour from the adsorbent at low pressure in heat exchange with the refrigerating chamber.

95 2. Refrigerating apparatus comprising a refrigerating chamber, an absorption machine consisting of a condenser, absorber and two evaporators, connected in operative cy-
100 cle, the elements being disposed within the refrigerating chamber with the exception of the absorber, and a receptacle adapted to contain dry ice in heat exchange with said condenser.

105 3. Refrigerating apparatus comprising a refrigerating chamber, an absorption ma-
chine consisting of a condenser, absorber and two evaporators, connected in operative cy-
110 cle, including conduit means between the con-
denser and one evaporator for the circula-
tion of an inert gas therebetween, the elements being disposed within the refrigerating chamber with the exception of the absorber, and a receptacle adapted to contain dry ice in heat exchange with said condenser.

115 4. Refrigerating apparatus comprising a refrigerating chamber, an absorption ma-
chine consisting of a condenser, absorber and two evaporators, connected in operative cy-
120 cle, including conduit means between the ab-
sorber and one evaporator for the intermit-
tent siphoning over of adsorbent solution,
the elements being disposed within the re-
frigerating chamber with the exception of the absorber, and a receptacle adapted to
125 contain dry ice in heat exchange with said condenser.

130 5. Refrigerating apparatus comprising a refrigerating chamber, an absorption ma-

chine consisting of a condenser, absorber and two evaporators, connected in operative cycle, the absorber and one evaporator being joined into one generator-absorber unit, containing a solid absorbent medium means for conducting heat from the refrigerating chamber to the generator-absorber and from the generator-absorber to the cooling medium, and a receptacle adapted to receive dry ice in heat exchange with said condenser. 70
